UNITED STATES PATENT OFFICE.

WILLIAM A. COPE, OF MULLINVILLE, KANSAS.

WINDOW AND DOOR LATCH.

1,113,197.

Specification of Letters Patent.

Patented Oct. 13, 1914.

Application filed October 1, 1913. Serial No. 792,898.

To all whom it may concern:

Be it known that I, WILLIAM A. COPE, a citizen of the United States, residing at Mullinville, in the county of Kiowa and State of Kansas, have invented certain new and useful Improvements in Window and Door Latches, of which the following is a specification.

This invention relates to a securing device which is intended to be used for holding either a door or a window in a closed position.

One of the objects of the invention is to so construct the device that it can be used for either purpose without any adjustment.

Another object of the invention is to so construct the device that when in place a window will be securely held in closed position with the securing device so located that it cannot be easily worked loose by a person outside the window.

Another object of the invention is to so construct the securing device that it may be used for extracting tacks as well as for securing a window or door in a closed position.

Other objects of the invention will appear in the course of the following specification wherein a preferred form of the invention is described.

This invention is illustrated in the accompanying drawings wherein:—

Figure 1 is a perspective view of the improved locking device; Fig. 2 is a perspective view of a key used in connection with the locking device shown in Fig. 1 when securing a door; Fig. 3 a sectional view showing the locking device applied to a window; and Fig. 4 is a sectional view showing the locking device applied to a door.

Referring to Fig. 1 it will be seen that this locking device comprises a plate 10 which may be formed of heavy sheet metal or may be formed by casting. This plate is provided at each end with a flange 11 which has a sharpened edge 12 and is provided with a notch 13. The notch 13 is provided so that when it is desired to use the device as a tack extractor the flange may be placed beneath the tack with the tack positioned in the notch and the device then tilted to extract the tack. Sharpened fingers 14 extend from opposite ends of the plate 10 and are intended to dig into the upper and lower sashes 15 and 16 as shown in Fig. 3 so that

a window may be securely held in a closed position. It should be noted that by having the fingers 14 positioned as shown, the upper and lower sashes will be forced apart a certain extent when the securing means is applied and thus held in tight engagement with the window frame. This will prevent the windows from rattling in case the wind blows. One end portion of the plate 10 is provided with a longitudinally extending slot 17 which is provided so that a tapered securing key 18 can be passed through the slot as shown in Fig. 4.

When this device is used to secure a window, the upper and lower sashes are first moved to a closed position and the device is then applied as shown in Fig. 3 with the sharpened fingers 14 embedded in the sashes. It will be impossible to open the sashes when this device is used since the device is positioned at an incline and therefore any movement to raise or lower the sashes will cause the points of the fingers to dig deeper into the wood of the window sashes.

When this device is used to secure a door the plate is positioned as shown in Fig. 4 with the sharpened flange at one end embedded in the door frame 19. The door 20 is then closed and the key 18 is then driven through the slot 17 until it extends partially across the door and partially across the door frame. By having the key tapered it causes a wedging action which will tighten the plate and securely hold it in position. An opening 21 is formed in the key so that it may be carried upon a key ring and thus danger of it being lost prevented. It should also be noted that the smaller end 22 may be of such size that the key can be used as a screw-driver.

What is claimed is:

1. A fastening device of the character described comprising a plate, and tapered penetrating fingers extending from one edge of said plate adjacent the opposite ends thereof and extending diagonally from the plate in opposite directions.

2. A fastening device of the character described comprising a plate, and penetrating fingers extending from opposite ends thereof, said fingers extending diagonally from the plate in opposite directions to each other.

3. A fastening device comprising a plate comprising a plate, and penetrating fingers

extending from opposite end portions of said plate in diverging relation to each other, one of said fingers being bent to extend beyond one of the side faces of said plate and the other of said fingers extending substantially flush with both of the side faces of said plate.

In testimony whereof I affix my signature in presence of two witnesses.

WILLIAM A. COPE.
